CLAIM

The ornamental design for combined pot and removable handle cover unit, as shown and described.

DESCRIPTION

FIG. 1 is a top perspective view of a combined pot and removable handle cover unit in exploded condition, showing my new design;

FIG. 2 is a side elevational view, the opposite side being a mirror image thereof;

FIG. 3 is a bottom perspective view in exploded condition; and

FIG. 4 is an enlarged fragmentary view of the inner bottom of the pot thereof.

FIG. 1

FIG. 2

FIG. 3

FIG. 4
